UNITED STATES PATENT OFFICE.

NATHAN C. BUTLER, OF CLEVELAND, OHIO.

FUSE PLUG.

Application filed October 8, 1920. Serial No. 415,629.

This invention relates to improvements in fuse plugs for use in electric installations.

The object of this invention is to provide a fuse plug comprising a main member having an exterior threaded contact for engagement in a suitable socket and a removable member carrying the fuse which has its ends secured to a center contact and to a peripheral contact, respectively, the last named contact being removably connected to the main contact member.

It is also the purpose of this invention to provide a removable member with an insulator extension between the two contacts for preventing arcing, to connect the fuse element to the peripheral contact in a simple and efficient manner, and to further engage the removable member in such a manner that it will hold the mica or other transparent window in place in the main member. Other objects of the invention are the provision of suitable gas vents, the provision of suitable grooves for holding the fuse wire in place, the provision of simple and efficient contact means between the main member and the fuse carrying member, and also to provide a simple and efficient means for anchoring the fuse wire.

Other objects of this invention will be apparent from the following description and claims when considered together with the accompanying drawing.

Fig. 1 is a side elevation of the fuse plug assembled; Fig. 2 is a side elevation of the fuse plug assembled with part of the main member broken away; Fig. 3 is a vertical section of the main member; Fig. 4 is an inverted plan view of the main member; Fig. 5 is a vertical section through the fuse carrying member; Fig. 6 is an inverted plan view of the fuse carrying member with part of the exterior contact broken away; and Fig. 7 is a top plan view of the fuse carrying member with part broken away.

The main member comprises the hollow tubular insulator portion 1 and the socket engaging member 2 which is formed of electroconducting material. The socket engaging portion 2 is secured to the insulator 1 by means of the struck-in portions 3 which securely engage the recesses 4 in the insulator 1. The tangs 5 are struck out of the member 2 and extend inwardly so as to engage the lower end of the insulator. The purpose of these tangs is to provide a means of electric contact between the fuse carry-

ing member and the socket engaging member when the parts are assembled, as will appear. The striking of these tangs 5 from the socket engaging member serves also to provide means of escape for the gases from the chamber within the fuse plug. The lower end of the insulator 1, as viewed in Fig. 3 of the drawing, is made of restricted diameter so as to provide an annular channel 6 between the socket engaging member and the lower end portion of the insulator 1. Then by the provision of the notches 7 in the lower end of the insulator 1 communication is afforded between the chamber within the fuse plug and the outside atmosphere. The avenue of communication between the chamber just referred to and the outside atmosphere is by way of the notches 7, which in fact amount to apertures or ports when the fuse carrying member is in full engagement with the socket engaging member, thence through the annular channel or duct 6 and thence through the openings 8 formed by striking out the tangs 5. The upper portion of the insulator 1 is formed with an interior shoulder for the seating of the transparent disk 9, such as glass, mica or the like, which is held in seated position by the contact of the upper end of the fuse carrying member when in full engagement with the socket engaging member, as viewed in Fig. 2. The lower portion of the socket engaging member 2 is screw threaded as indicated at 10 to receive the thread 11 on the fuse carrying member.

The fuse carrying member comprises a body of electroinsulating material having a base portion 12, the intermediate portion 13 of reduced diameter and the upper tapering extension 14, as viewed in Fig. 5. The fuse carrying member itself is hollow throughout its full extent, as indicated at 15, the opening through the base portion 12 being comparatively restricted. The upper end of this member is formed with a groove 16 for the reception of the fuse wire 17 which further extends through the groove 18 formed in the intermediate portion 13. This end of the fuse 17 is anchored beneath the split ring 19 which firmly engages the intermediate portion 13 of the insulator and seats upon the base portion 12. Ring 19 is of electroconductive material and forms contact with tangs 5 upon full engagement of the fuse member with

- the main member. The other end of the fuse 17 is anchored by means of electric contact member 20 which has a form somewhat similar to that of a bifurcated rivet.
- 5 The head of the contact 20 seats in the circular depression 21 in the insulator base portion 12 and firmly clamps therein the end of the fuse wire 17. The prongs 22 of the contact 20 have their upper ends, as
- 10 viewed in Fig. 5, bulged outwardly as indicated at 23 so as to firmly engage the inner wall of the tubular insulator when the contact 20 is inserted therein. The prongs 22 separately join the head portion of the
- 15 contact 20 and have sufficient resilience for ready insertion and proper engagement in the insulator. Instead of employing a single fuse wire, a plurality of wires may be employed and suitable grooves provided
- 20 in the upper end and in the intermediate portion 13 of the insulator member for the reception of such wires as may be desired.

It will be seen from the foregoing that the removable fuse carrying member comprises an insulator body portion, a center contact member and an annular contact member, together with a fuse which is electrically connected to the contact members; and that this fuse carrying member can be

25 assembled and removably secured in the socket engaging member; furthermore, when these parts are so assembled the upper end of the fuse carrying member will hold the glass or mica disk in proper seating position without interference by the fuse itself which lies in the groove 16.

It will also be seen that gases formed within the fuse plug are permitted to escape to the outside atmosphere. Furthermore, the tangs 5 constitute a simple and efficient means for the provision of a gas vent, and at the same time serve as contacts for engagement with the split ring 19 when the parts are fully assembled. The engagement of tangs 5 with the insulator member

30 1 serves also as an additional means of securing the member 2 against displacement toward the other end of member 1. The particular means for anchoring the ends of

35 fuse wire permit ready renewal of such wire while the grooves through which the fuse extends serve to prevent displacement of the same. Altogether this invention constitutes a simple, economical and yet an extremely efficient fuse plug.

Other advantages flowing from this invention will be apparent to those familiar with the art to which it relates.

What I claim is:

- 60 1. In a fuse plug, a main member comprising an insulator and a socket engaging

member secured thereto, inwardly extending tangs struck out of said socket engaging member, a fuse member removably secured within said socket engaging member and having a contact member for engagement with said tangs, a second contact member carried by said fuse member, and a fuse element extending between said last named contacts.

2. In a fuse plug, a main member comprising an insulator and a socket engaging member having apertures therethrough, the inner end of said insulator being formed with a channel having communication with said apertures and with the interior of said insulator member, a fuse member removably secured in said socket engaging member and having electric connection therewith.

3. In a fuse plug, a main member comprising an insulator, a socket engaging member secured to said insulator and having inwardly extending tangs struck out thereof at the inner end of said insulator and providing apertures, the inner end of said insulator being formed with a channel having communication with said apertures and with the interior of said insulator, said tangs engaging the inner end of said insulator, a fuse member removably secured to said socket engaging member and having electric connection therewith.

4. In a fuse plug, a main member comprising an insulator and a socket engaging member secured thereto and having inwardly extending tangs struck out thereof and providing apertures therethrough, the inner end of said insulator being formed with an annular channel having communication with said apertures and with the interior of said insulator, a fuse member removably secured to said socket engaging member and being provided with a contact portion for engagement with said tangs, and electric connections therethrough.

5. In a fuse plug, a main member comprising an insulator and a socket engaging member, said socket engaging member being provided with inwardly extending contacts intermediate the ends thereof, a fuse member removably secured within and to said socket engaging member, a contact ring carried by said fuse member and being adapted for electric contact with the contacts upon said socket engaging member, a second contact carried by said fuse member and a fuse wire extending between the contacts upon said fuse member.

In testimony whereof I hereby affix my signature.

NATHAN C. BUTLER.
